UNITED STATES PATENT OFFICE

EDWARD THOMAS ALLAN, OF CINCINNATI, OHIO, ASSIGNOR TO THE UNION THREAD COMPANY, OF CINCINNATI, OHIO, A CORPORATION OF OHIO

THREAD PACKAGE

Application filed January 21, 1929. Serial No. 334,048.

This invention relates to improvements in thread packages, more especially of the bobbin type in which a central cylindrical support is provided and upon which the thread is wound by automatic machinery in a criss-cross or herring-bone arrangement so that the package is self supporting without the employment of end disks.

According to the present invention, this thread package is so constructed and arranged that the thread package may be employed, for example, on a sewing machine, and in particular, the package may be located on a receiving stand having a stand pin of any of several sizes.

A further feature of the invention is the provision of a core for such a package which can only be placed on a sewing machine in the proper position for the correct withdrawal 20 of the thread therefrom, and this end is attained by the provision of means which prevent the placing of the package on the stand in an incorrect or inverted position.

Another feature of the invention is the provision of a thread carrier or flier which is of simple and cheap construction, is mounted on the package to be packed and shipped therewith, and operates in conjunction with the package to place a proper tension upon the thread as withdrawn from the package, the actual tension being regulated automatically 30 in proportion to the decrease of diameter of the package as the thread is consumed.

A still further feature of the present invention is the employment of reinforcing members for the core of the package which are permanently fixed thereto and therefore form a permanent support for identification data with respect to the thread on the package.

The package according to the present invention is shown on the accompanying drawings in one illustrative example of execution, in which:

Figure 1 is a view substantially in vertical diametrical section through the package, which is shown as located upon a supporting stand.

Fig. 2 shows a bottom view of the package 50 as ready for packing and shipment.

Fig. 3 is a top view of the package with the thread carrier or flier drawn out into position for operation.

According to this invention, a tubular core is provided upon which the thread is wound by automatic machinery in a so-called "herring-bone" arrangement so that the package is self sustaining. Stiffening members are provided at the top and bottom of this core, the one at the bottom being adapted to fit over any of a number of sizes of stand pins, while the one at the top is substantially imperforate so far as location over a stand pin is concerned: and hence the thread package can only be placed on a stand in the correct position. In addition to this core construction, the upper reinforcing member has a small aperture to receive a thread carrier or flier, this carrier or flier being made in a peculiar manner so that it is adapted, during shipment, to be located substantially within the package and thereby is always at hand and ready for use by the customer, and on the other hand, its construction and arrangement enable it to cooperate with the package itself 70 to maintain a correct and desirable tension upon the thread as withdrawn from the package.

In the drawings, the tubular core 10 is illustrated as of cylindrical shape, and the thread 11 is wound thereon. The core is intended to fit over a stand pin 12 of a stand 13 which may be mounted in any desired manner on a sewing or other machine which is to consume the thread. This stand has an extension 14 to receive a spindle 15 having its upper end bent into a horizontal position so that the thread guiding eye 16 thereon is located above the stand pin 12, and hence in the axial line of the tubular core 10 when in position on the stand 13.

In order to center and guide the core and package as a whole with respect to the stand 13 and its pin 12, a cupped sheet metal reinforcing member 17 is inserted into the lower end of the core 10, and the edge 17 thereof is formed with scallops or teeth which bite into the inner wall of the core 10 and are thus immovably held therein. As shown in Fig. 2, crossed notches 19 are formed in the rein-

forcement 17, with their crossing at the axis of the core 10. In employment, the package is placed over the stand pin 12 and forced down until the stand pin 12 causes the tongues formed by the slots or notches 19 to be bent upward, conforming themselves to the stand pin as shown in Fig. 1.

At the upper end of the tubular core 10 is provided a similar reinforcing member 20 which has no opening therethrough of sufficient size to receive the stand pin 12, thus preventing the placing or forcing of the stand pin in the upper end of the thread package. The reinforcing member 20 is likewise of cup shape and has the scalloped or toothed edge 21, preferably forced outward during the assembly of this reinforcing member 20 in the core 10, in such manner as to bite into the core and thus prevent any downward movement of the reinforcing member 20 within the core 10 without tearing and destroying the parts, i. e., thus warning the operator that the thread package is not in the correct position.

This construction furthermore has the advantage that the reinforcing members may be formed of lithographed sheet metal, bearing thereon the necessary and desired identification for the thread, and as shown in Figs. 2 and 3, the lower reinforcing member 17 is marked with the length and size of the thread while as shown in Fig. 3, the upper reinforcing member 20 is marked with a trade-mark or other brand indication. Any attempt to remove these reinforcements will result in damage to the core, and thus give a clear indication that a substitution has been attempted, and assure the customer that an unbroken package comes from the desired source.

It is preferred to form the upper reinforcing member 20 with a central aperture 22 and a lateral aperture 23 spaced therefrom. The thread carrier or flier is shown in Figs. 1 and 2 as having a principal arm 24 rebent at a point beyond the jacket surface of the thread package, to afford a secondary arm 25 extending parallel to the arm 24. As shown in Fig. 1, the thread flier has another bent portion 26 which is substantially vertical during the employment of the flier and terminates in a horizontal hook 27. The vertical portion 26 extends through the central aperture 22, and the hook 27 is located beneath this aperture.

After the thread has been wound upon the tubular core 10, and the package is ready for preparing for shipment, the thread flier is located in the position shown in dotted lines in Fig. 1, i. e., it is wholly within the core 10, and only the extreme rebent portion is above the reinforcement 20. The purchaser, however, upon locating the package on a stand 13, pulls upward on this loop and moves the arms 24, 25 into the position shown in Figs. 1 and 3, whereupon the flier is at

rest upon the top of the package, lying against the upper edge of the core 10 and having a frictional bearing thereon. The thread from the package is led through the loop between the arms 24, 25 and thence upward to the guide eye 16, and from thence to the sewing machine or other place of employment.

As thread is drawn from the package, the pull against the arm 24 will cause the flier to rotate about its bent portion 26, and by the resting of this flier upon the upper end of the core 10, a substantially uniform frictional resistance to the rotation of the flier is produced. The force tending to cause the rotation of the flier is likewise substantially uniform but is applied to the arm 24 at a distance from the pivot point at 26 which varies with the diameter of the thread winding 11. As the diameter of the thread in the package becomes less, the point of application of this force approaches the core, and since the lever arm of application of this force grows less while the friction remains the same, a relatively greater frictional effect is opposed to the movement of the flier, so that an automatic increase of the friction tension is occasioned.

It is obvious that the invention is not limited to the form of employment shown, but that it may be applied in many ways within the scope of the appended claims.

What is claimed as new and desired to secure by Letters Patent is:

1. In a thread package, a core to receive the thread on its outer surface and open at both ends, upper and lower reinforcing members inserted in the ends of said core and secured inside the same, said lower reinforcing member being adapted to fit over the stand pin of a thread stand whereby thread may be drawn therefrom to feed a thread consuming mechanism, said upper member being substantially closed so that it cannot be fitted over the stand pin and being located adjacent the upper end of said core so that it is encountered by the stand pin and thus prevents the placing of the thread package on said stand in an upside down position.

2. In a thread package, a core open at both ends and adapted to receive the thread, upper and lower reinforcing members inserted in said core to stiffen the same, said upper reinforcing member being substantially closed to prevent the placing of said package upside down upon the thread stand, said lower reinforcing member having cross notches to provide tongues which are located in a plane transverse to the axis of the core and cooperating with the stand pin of the thread stand to center the package upon the stand, said tongues being located a lesser distance apart than the diameter of the stand pin and being deformable by engagement with the stand pin so that they thereafter co-

operate with the stand pin to prevent bodily or rotational movement of the package upon the stand.

3. In a thread package, a hollow core open at both ends and adapted to receive the thread, an upper reinforcing member substantially closed so that the package is prevented from being mounted upside down on the thread stand, said upper reinforcing member having tongues engaging the wall of said core so that the member can only be removed from said core by mutilating the package, and identifying markings upon the outer surface of said reinforcing member whereby the reinforcing member and its markings may be removed from the package only by a mutilation which will reveal such removal.

4. In a thread package, a core open at both ends and adapted to receive the thread on the external surface thereof, an upper reinforcing member located in said core, a thread flier pivoted in an aperture of said upper reinforcing member, and resting when in operative position upon the upper edge of the core whereby the friction between the said flier and said core opposes the movement of said flier about its axis.

5. In a thread package, a core adapted to receive the thread on the external surface thereof, an upper reinforcing member substantially closing the upper end of said core, said member having two apertures therein, a thread flier formed of wire with a long and a short thread guiding arm, a laterally bent pivot portion on said long arm, and a retaining portion terminating said pivot portion, said pivot portion being adapted to rotate in one of said apertures while thread is being drawn from said package between said arms and having a frictional resistance opposed thereto by the contact of the flier with said core, said arms being adapted to slide into said apertures so that the thread flier may be located substantially within said core.

6. A thread flier for a thread package, formed from a single piece of wire, and having a long and a short arm extending in substantial parallelism for the length of the short arm, said long arm having a lateral offset pivot portion and terminated by a retaining portion extending in a plane substantially parallel to said arms.

7. In a thread package, a core adapted to receive the thread, a sheet metal reinforcing member inserted in said core at the bottom of the package to stiffen said core, said reinforcing member having cross notches to provide tongues located substantially in a plane transverse to the axis of the core, said notches being of lesser width than the diameter of the stand pin so that the tongues are adapted to be engaged by the stand pin in placing the package upon the stand pin, said tongues being deformable thereby, so that said tongues

may cooperate with the stand pin to locate the package in predetermined position upon the thread stand and thereafter cooperate with the stand pin to prevent bodily or rotational movement of the package upon the stand.

In testimony whereof, I affix my signature.
EDWARD THOMAS ALLAN.
